UNITED STATES PATENT OFFICE

126,033

DESIGN FOR A DRESS ENSEMBLE

Julia Richards, Brooklyn, N. Y.

Application January 21, 1941, Serial No. 98,213

Term of patent 3½ years

To all whom it may concern:

Be it known that I, Julia Richards, a citizen of the United States, residing in Brooklyn, New York city, in the county of Kings and State of New York, have invented a new, original, and ornamental Design for a Dress Ensemble, of which the following is a specification, reference being had to the accompanying drawing, forming part thereof.

of the ensemble shown in Figure 1; and

I claim:

The ornamental design for a dress ensemble,
substantially as shown.

JULIA RICHARDS.
